UNITED STATES PATENT OFFICE

2,490,441

CALLING LINE AND PARTY IDENTIFICATION
IN AUTOMATIC TELEPHONYAmos E. Joel, Jr., New York, N. Y., assignor to
Bell Telephone Laboratories, Incorporated, New
York, N. Y., a corporation of New York

Application May 22, 1947, Serial No. 749,827

14 Claims. (Cl. 179—8.5)

1

This invention relates to telephone systems and more particularly to a system in which it is desirable to register in equipment common to a plurality of subscribers' lines the identity of any one of the lines which may have originated a call.

In systems for this purpose, which have been proposed heretofore, it has been necessary to provide individual networks and special means for obtaining access to these networks for identification. Such a system is disclosed and claimed in the application of J. W. Gooderham, Serial No. 448,782, filed June 27, 1942.

In the crossbar system means exists for obtaining access to the sleeve of each line, when that line is called, to determine the busy or idle condition of that line. Such means is disclosed and claimed in United States Patent 2,201,573, granted to W. W. Carpenter et al., May 21, 1940.

In accordance with the present invention the same means is employed for connecting with the sleeve conductor of a line when that line is calling or when it is called.

In addition, groups of tone transmitting networks are provided common to the lines with means for connecting the sleeve conductors of lines to the networks during the different stages of identifying the calling line.

As set forth in the above-identified Carpenter et al. patent, in the crossbar system there is a set of terminals for each line and a set of terminals for each line designation which terminals are cross-connected to transmit to a control circuit known as a terminating marker, the location, class, and busy or idle condition of a called line, the last information being obtained from the sleeve conductor of the line. In order to permit more than one marker to operate at a time the designation terminals are divided among a number of frames, the numbers being assigned by groups of one hundred to the frames. Any one frame may have from one to eight groups of numbers identified by one hundreds digit but the hundreds digits may or may not be in sequence. Associated with each line in the crossbar line switches is at least one metering conductor.

In accordance with another feature of the invention, means is provided for employing the metering conductor of a calling line for determining, and obtaining access to, the frame to which the sleeve conductor is cross-connected and employing the sleeve conductor for identifying the line on the frame.

These and other features of the invention will

2

be more apparent from a consideration of the following description read in connection with the drawing in which:

5 Figs. 1 and 8 show three subscribers' lines, together with the switches and district junctors over which outgoing calls are extended;

Fig. 2 shows in schematic form an outgoing trunk and an associated outgoing sender;

10 Figs. 3 to 7 and 13 to 17 show one of a plurality of identifiers;

Fig. 3 showing the sender-identifier connector;

Fig. 4 showing the frame group progress relays;

Fig. 5 showing the frame group identification control circuit;

15 Fig. 6 showing the hundred block and twenty block identification control circuit;

Fig. 15 showing the detector input connector relays;

Fig. 16 showing the detectors and output relays;

Fig. 17 showing the detector output connector relays;

Figs. 9 and 12 show the number group frame;

Fig. 9 showing the cross-connecting racks, and

30 Fig. 12 showing the hundred block and twenty block relays;

Fig. 10 shows the marker number group multicontact connector relays;

Fig. 11 shows the identifier number group multicontact connector relays; and

35 Fig. 18 shows the manner in which the other figures are to be arranged.

The control circuits of the identifier have been patterned after the control circuits of the above-40 identified Gooderham application and reference is made to that application for circuit details which have been omitted to simplify the present disclosure.

Briefly, when a calling line initiates a toll call, 45 the line is extended to a trunk outgoing to the toll office and an outgoing sender is attached to the trunk to control the apparatus at the distant office and to transmit thereto the number of the called line. This sender also includes a calling line register and a recorder or ticketer which records the details of the call for charging purposes. When the sender has received the called number, it associates itself with an idle identifier which applies an identification tone to the sleeve conductor of the trunk whence it is returned

through the established connection to the sleeve conductor of the calling line and through a condenser at the district junctor to the metering conductor associated with the calling line. The metering conductors of all lines associated with one number group frame are connected through the individual message register or through a special network in multiple to a tone coil individual to the frame. The identifier is provided with a plurality of detectors which it connects with the frame tone coils by groups until the applied tone is detected, whereupon the identifier connects with the corresponding number group frame. The identifier now operates all eight of the hundred block relays on the selected frame and operates the first twenty block relay over the contact of each hundred block relay. Each twenty block relay connects the sleeve conductors of twenty lines to the identifier where they are connected to networks which are in turn connected in multiple to a set of tone coils, one for each ten lines, thereby testing one hundred and sixty lines at a time. These tone coils are connected with the detectors which detect the tone applied to the sleeve of the calling line if it is included in the group being tested. If not, a set of twenty block progress relays operates to release the first twenty block relays and operate the second twenty block relay over each hundred block relay. When the tone is detected, one of the hundred block relays is held operated in the number group frame to supply the thousands and hundreds digits of the calling line number, and a twenty block progress relay and an even or odd tens relay are held operated to supply the tens digit and to connect the ten sleeve leads to a set of ten networks which are in turn connected to the detectors to identify the individual line and operate a units register relay which supplies the units digit. When the units register relay has been operated the line number is transmitted to the calling line register in the sender where it is transferred to the recorder along with the other information necessary for filling the call.

Party line—Ring party

When the subscriber at substation 100 wishes to make a toll call, he removes his receiver from the switchhook, thereby initiating a series of operations resulting in the connection of his line with an idle district junctor such as junctor 107 over primary line switch 103 and secondary line switch 104 and with an idle originating sender 123 over a sender link 122. He then dials the number of the wanted line which is registered in the originating sender 123. The sender 123 connects with an idle originating marker 125 through the marker connector 124 and transmits the designation of the wanted office to the marker which functions to connect the district junctor 107 through a set of switches represented by switches 114 and 115 to a trunk outgoing to the toll office. When this connection has been established, a circuit is closed from battery through the left winding of the trunk-line relay 201, right contact of relay 200, conductor 117, through the switches 115 and 114 and sender link 122 to a bridge established in the sender 123 and back to conductor 116, left contact of relay 200, right winding of relay 201 to ground. Relay 201 operates relay 202 which in turn operates the start relay 203 of the trunk connector 204 which serves to connect the trunk with an idle outgoing sender 205. This sender includes a called line number register 206 which serves to control the extension

of the call to the called line, a party identification circuit 207 for indicating when the tip party of a two party line is calling, a calling line number register 208, operated by the line identifier and a recorder or ticketer 209 for recording the details of the call for charging purposes.

When the sender has been attached to the trunk, relay 200 is operated to transfer the tip and ring conductors from relay 201 to the sender 205, after which the originating sender 123 transmits the called line designation to the called line number register 206. When the designation has been received, relay 210 operates to start the operation of the line identifier. The sender proceeds to control the completion of the connection in the appropriate manner.

When the control equipment at the originating office has completed its functions relays 108 and 109 are operated in the district junctor 107 and the calling line is connected through to the sender 205, where the party identification circuit functions to test whether or not the calling substation is a tip party on a party line. Assuming that substation 100 is the ring party, the line will be ungrounded and relay 211 remains unoperated. The above-identified Gooderham application discloses in detail a typical operating circuit for such as relay 211, as well as typical circuits for such as relays 210 and 216 to be referred to hereinafter and for such as relay 200 previously mentioned. Patent 2,235,803 to W. W. Carpenter of March 18, 1941 discloses in detail typical operating circuits for certain relays of district junctor 107, such as relays 108, 109, 111 and 112.

Several identifiers are provided for use by a number of groups of trunks and a connecting arrangement similar to the standard marker connector is used to connect a trunk with an idle identifier. When relay 210 operates, it connects battery over the back contact of relay 216 to conductor 212 operating relay 300 if no other trunk of the group is using the connector at the time. Relay 300, in turn operates relay 301, which extends battery on conductor 212 to the identifier preference relays 310, 311, etc. If the preferred identifier is idle, relay 320 is unoperated and battery is extended over the back contact of relay 320 to the winding of relay 310 and ground. Relay 310 operates in turn operating relay 330. With relays 301 and 330 operated, a plurality of circuits are completed between the trunk and the identifier. One circuit extends from ground over the contacts of relays 330 and 301, conductor 341 through the trunk connector 204 to the winding of relay 214 and battery. Relay 214 extends the sleeve conductor 118 of the trunk over its contact, through connector 204, conductor 215, contacts of relays 301 and 330 to conductor 342.

Since relay 211 is normal, to indicate that a ring party is calling, a circuit is closed from ground over the back contact of relay 211, conductor 213, contacts of relays 301 and 330, conductor 340, winding of relay 413 and battery. With relays 330 and 413 operated, a circuit is closed from battery through the winding of relay 408, right back contact of relay 409, front contact of relay 413, conductor 414 to ground at a contact of relay 330. Relay 408 operates in this circuit, connecting a source of 270 cycle identification tone, through resistance 415 to conductor 342 and as above traced to sleeve conductor 118, through the switches 115 and 114, and thence over two paths to the number group frame. One path extends over the inner lower contact of relay 109, back contact of relay 112, lower contact of relay 108,

resistance 110, through line switches 104 and 103, conductor 119, to the individual sleeve cross-connecting terminal 950 on the number group frame rack 900. The other path extends through condenser 113, outer lower front contact of relay 109, back contact of relay 112, back contact of relay 111, which is not operated since the calling line is a ring party, through the line switches 104 and 103, to metering conductor 120, through message register 835 to conductor 850 and thence to ground through the primary winding of tone coil 910.

All of the message rate subscribers' lines which appear on this number group frame have their message registers connected with ground through the winding of tone coil 910 whether party line or individual line and there is a similar tone coil 911, etc. for each of the other number group frames. Since the message registers of an office are arranged on special racks in groups corresponding to blocks of one hundred consecutive directory numbers, the connection of the message registers to the proper number group frame coil is easily accomplished. Individual lines having no message registers have their metering conductors connected directly to the primary winding of the corresponding number group tone coil.

For two party flat rate lines, a second or tip set of coils is provided for the tip party and the single metering conductor in the line switches is connected in multiple through a pair of resistance and condenser networks to the ring coil of the number group in which the ring party number appears and to the tip coil of the number group in which the tip party number appears.

As has been indicated in the drawing, the numbers assigned to the two parties on a line may appear on the same number group frame as in the case of substations 100 and 101 or may appear on different number group frames as indicated for substations 800 and 801.

The identifier first looks for the number group frame to which the calling line is assigned. For the purpose of recognizing the identification tone, a set of sixteen detectors 1600 to 1615 are provided, which are substantially the same as those employed in the above-identified Gooderham application. Since there are more number group frame tone coils than the number of detectors, which is made sufficient for subsequent steps of the identification, the number group frames are tested in groups, and a set of progress relays 400 to 405 is provided for controlling the progressive tests of the groups.

When the identifier is ready to function, the timer 1703 causes ground to be connected to a number of off-normal conductors including conductor 516. Ground on conductor 516 completes a circuit over the left back contact of relay 512, conductor 716, left back contact of relay 409, conductor 417, contact 4 of relay 711, conductor 724, to the winding of relay 1502 and battery, to extend the input circuits of the detectors 1600 to 1615 toward the frame tone coils.

Ground on conductor 516 also completes a circuit over the back contacts of relays 513, 510 and of the frame register relays 502, 501, 500, etc. to battery through the winding of number group test start relay 511 and battery. Relay 511 operates, locking to ground over the back contact of relay 513 independent of the frame register relays. With relay 511 operated, a circuit is closed from ground on conductor 516, over the back contact of relay 512, contact 3 of relay 511, conductor 517, contact 1 of relay 405, conductor 418, contact of relay 339 through the windings of

frame group relays 302 and 303 to battery. Relays 302 and 303 operate to connect the secondary windings of the tone coils on the first group of number group frames to the contacts of relay 1502 and thence to the input circuits of the detectors.

Ground extended to conductor 517 as above traced also completes a circuit over contact 3 of relay 405 to the winding of relay 410 and battery. Relay 410 operates and at its lower contact connects ground to conductor 419, completing a circuit for relay 1702 which connects the frame register relays 500, etc. to the output relays of the detector.

Since the calling substation 100 has been shown as connected to the first number group frame in the first group of frames the tone connected to the primary winding of coil 910 will be transmitted from the secondary winding of coil 910 through cabled leads 930 and 932 over normal contacts of relay 306, contacts of relay 302, cabled leads 343, contacts of relay 1502 to the input of detector 1600. The detector 1600 responds to the identification tone, operating polarized relay 1620 in its output circuit.

When relay 1502 operated it connected ground to the armatures of all of the polarized relays. At the same time that timer 1703 caused relay 1502 to be operated it connected battery to conductor 1706, preparing relays 1640 to 1655 for operation.

Therefore, when detector relay 1620 operates to indicate that the identification tone has been detected by detector 1600, a circuit is closed from ground at the front contact of relay 1502, contact of relay 1620, winding and normal contact of output relay 1640 to battery on conductor 1706. Relay 1640 operates, locking to battery over its alternate contact and closes a circuit for relay 500 in the frame register. This circuit may be traced from battery over the upper front contact of relay 1640, conductor 1660, front contact of relay 1702, conductor 1707 through cable 1708, left winding of relay 500, conductor 518 through cable 1708, front contact of relay 1702, conductor 1709, lower front contact of relay 1640, back contacts of the remaining output relays 1647, 1648, 1649, 1654, 1655, etc. to ground.

Relay 500 operates in the above traced circuit and locks in a circuit from ground through its right winding and contact 4, contact 1 of relay 511 to battery through the winding of relay 510. Relay 510 operates in this locking circuit for relay 500. At its contact 3, relay 500 also closes a circuit from off-normal ground to conductor 523 and thence over a contact of relay 410, and conductor 426 to the winding of relay 306 and battery. Relay 306 operates, disconnecting the secondary winding of the tone coils on this number group frame from the test detector 1600 to prevent any other identifier from attempting to connect with this number group frame.

With relays 306, 500 and 510 operated a circuit is closed from battery through the winding of slow to operate relay 512, front contact of relay 510, contact 6 of relay 500, conductor 519, front contact of relay 410, conductor 426, to ground at the right contact of relay 306. Relays 510 and 500 open the operating circuit of relay 511, but that relay remains operated under the control of relay 513 to off-normal ground. When relay 512 operates after an interval determined by its slow to operate character, it disconnects ground from conductor 517, releasing relays 302, 303, 410 and 75 from conductor 716, releasing relay 1502, the re-

lease of relay 410 in turn releasing relay 1702. The release of relay 1502 disconnects the tone coils from the detectors and ground from the detector relays so that relays 1620 and 1640 also release.

With relay 500 operated, the identifier is ready to seize the number group frame to identify the calling line. Both terminating markers and identifiers use the number group frames, to which they are connected by multicontact relays. Each marker and each identifier has a preference relay and a multicontact relay for each number group frame, the preference relays for all markers and identifiers for one number group frame being arranged in a chain circuit to prevent a marker and an identifier from seizing a number group frame at the same time.

Relay 500, when operated, closed a circuit from battery over the back contacts of the other frame register relays 502, 501, etc., contact 2 of relay 500, conductor 520, contact of relay 410, conductor 421, winding and normal contact of preference relay 1111 to ground over normal contacts of other identifier and marker preference relays 1001, 1011, etc. Relay 1111 locks in a circuit from ground over its right contact winding and outer left contact, conductor 1112 to battery at the back contact of relay 1704, and opens the operating circuit for the marker preference relays 1101, which precede it in the chain. At its left front contact it connects ground supplied over the back contacts of relay 1101, etc. to the winding of multicontact relay 1112 to connect the number group frame with the identifier. These operations are completed before slow relay 512 operates.

With the multicontact relay 1112 operated, the identifier is ready to employ the number group frame to test the sleeve conductors to identify the calling line. As described in the above-identified patent to Carpenter et al., the sleeve conductors of subscribers' lines are connected to terminals at the number group frame where each one is cross-connected with a terminal individual to the subscriber's line number. To give the marker access to that sleeve for testing there is a hundred block relay for each one hundred consecutive numbers, there being a maximum of eight hundred block relays on one frame, which may or may not correspond to consecutive hundreds digits. Each hundred block relay closes circuits for operating five twenty block relays, each of which connects the sleeve conductors of twenty consecutively numbered lines over contacts of the multicontact relay to twenty test circuits in the marker by which it tests these conductors for the busy or idle condition of the associated line. The marker operates one hundred block relay and one twenty block relay as determined from the called line number.

With relay 1112 operated, ground is connected to conductor 1120 completing a circuit over the back contact of relay 602, conductor 606, over the back contacts of hundreds register relays 1417, 1410, etc., conductor 1440, back contact of relay 605 to the winding of start relay 600 and battery. Relay 600 operates, locking to ground over its contact 2, and contact 3 of relay 715 and closes a circuit from ground over the back contact of relay 601, contact 3 of relay 600, conductor 607, and thence in parallel through the windings of relays 1700 and 1500 to battery. Relay 600 also connects ground to conductor 608 which extends over back contacts of the hundreds register relays 1410 to 1417, conductor 1441, through the wind-

ing of relay 1405 to battery. Relays 1405, 1500 and 1700 operate.

With relay 1405 operated, ground on conductor 608 is extended over the eight back contacts of relay 1404, conductors 1451 to 1458 through cable 1450, contacts of relay 1112, conductors 1121 to 1128 through cable 1130 to the windings of the eight hundred block relays 1200 to 1207 at the number group frame. All of these relays operate.

Relays 1500 and 1700 prepare the input and output circuits for the detectors. With relay 1500 operated, ground on conductor 608 is also extended as above traced over the back contacts of the hundreds register relays 1410 to 1417 to conductor 1441, contact of relay 1500, conductor 1510, contact 3 of relay 1312, contact 9 of relays 1304, 1303, 1302, and 1301 to the lower winding of relay 1300 and battery. Relay 1300 operates in this circuit. Ground on conductor 1510 also extends over contact 4 of relay 1311 to the winding of relay 1310 and battery, operating relay 1310. Relay 1500 also closes a circuit from ground in the timer 1703 over conductor 1511, contact of relay 1500, conductor 1512 to the winding relay 1311 and battery. Means, not shown, is provided in the timer to insure that relay 1311 operates for the first time only after a predetermined time has elapsed following the closure of this circuit.

With relay 1300 operated and relay 1311 non-operated, a circuit is closed for operating the first or zero twenty block relay in each hundred block. This circuit may be traced from ground over contact 3 of relay 1311, contact 3 of relay 1300, conductor 1313 through cable 1315, contact of relay 1112, conductor 1151 through cable 1130, over the front contact of hundred block relay 1200 to the winding of twenty block 1220 and battery, over the front contact of hundred block relay 1207 to the winding of twenty block 1210 and battery and over the contacts of the remaining hundred block relays to the windings of the first twenty block relay in each hundred block.

Each twenty block relay connects the sleeve conductors of twenty consecutively numbered lines together for a group test. For example, the sleeve conductor 119 of the calling line 100, which is cross-connected at the number group rack 900 to conductor 940 is now extended through cable 942, over a contact of relay 1220, conductor 1230 through cable 1240, contact of relay 1112, conductor 1140 through cable 1142, through the condenser resistance network 1460 to the primary winding of tone coil 1420. The other nine lines having the same even numbered tens digit in this group of twenty are connected through nine other networks to the primary winding of tone coil 1420. Assuming that line 800 has a number in this group of twenty numbers but with the odd tens digit, its sleeve conductor 834 will be cross-connected at rack 900 to a conductor leading to a contact of twenty block relay 1220, for example, to conductor 941 and will be extended through cable 942, contact of twenty block relay 1220, conductor 1231 through cable 1240, contact of relay 1112, conductor 1141 through cable 1142, to network 1461 and the primary winding of coil 1428.

Similarly, each operated twenty block relay extends twenty sleeve conductors to twenty networks, the networks associated with lines having even and odd tens digits being connected in multiple to the primary windings of separate coils like coils 1420 and 1428.

patent previously mentioned, the terminals individual to a line designation at the number group frame in addition to the one cross-connected to the sleeve conductor of the line to which the particular designation is assigned, also includes two other terminals over which the marker receives an indication of the location of the line and an indication as to which of three classes the line belongs. These three classes are one class including individual lines and ring parties on party lines, a second class including tip parties on party lines and a third class for trunks associated with private branch exchanges.

In order to check that the line detected is of the proper class and to distinguish between the two parties on the same line in the rare event that their numbers lie in the same group of ten, the polarized relays of the detectors at this time are supplied with ground over the class cross-connections in the identifier and the number group frame, so that only those detectors connected to sleeve conductors of lines of the proper type may be effective. For example, ground is connected to the armature of relay 1620 over a circuit which may be traced from ground at the back contact of relay 712, contact 8 of relay 711, conductor 716, back contact of relay 409, conductor 411, contact 4 of relay 711, conductor 725, contact of relay 1402, conductor 1470 through cable 1471, contact of relay 1112, conductor 1171 through cable 1130, contact of twenty block relay 1220, conductor 1251 through cable 942, cross-connecting terminal individual to the calling line on rack 900, jumper 943, cross-connecting terminal on class rack 902, conductor 944 through cable 942, contact of relay 1220, conductor 1252 through cable 1130, contact of relay 1112, conductor 1143 through cable 1144, contact of relay 1501 to the armature of relay 1620.

When relay 1620 operates in response to the identification tone, it extends this ground through the winding of relay 1640 to battery over conductor 1706. Relay 1640 operates in this circuit completing a circuit from battery over its upper front contact, conductor 1660, contact of relay 1701, conductor 1712 through cable 1713, winding of relay 701, conductor 717 through cable contact of relay 1701, conductor 1709, lower front contact of relay 1640 to ground over the lower back contacts of the remaining output relays 1641, etc. Relay 701 operates in this circuit and closes a locking circuit for itself from ground through its right winding and contact 4, contact 6 of relay 711, to battery through the winding of relay 710. Relay 710 operates in this circuit holding relay 701 operated and closing a circuit from battery through the winding of relay 712, front contact of relay 710, contact 2 of relay 701, contact 1 of the other units register relays 702, 703, etc. back contact of relay 713 to ground over conductor 609 as previously traced. Relay 701 opens the operating circuit of relay 711 but that relay remains locked over the back contact of relay 713 to ground on conductor 609. Relay 712 when operated as above described locks over its contacts under the control of relay 711 and at contact 1 disconnects ground from conductors 716 and 726 thereby removing ground from the detector relay armatures and releasing relays 1501 and 1701 to restore the detectors and output relay 1640 to normal.

At contact 2, relay 712 closes a circuit from ground at the contact of marker preference relay 310, conductor 344, contact 6 of relay 701, contact 2 of relay 712, conductor 718, to the wind-

ing of relay 1704 and battery. With relay 1704 operated, the identity of the calling line is transmitted to the calling line register 208 of the sender. Relay 1704 also opens the locking circuit of the number group preference relay 1111, permitting that relay and relay 1112 to release and restore the number group frame.

The hundred block relay 1200 on the number group frame is assigned to a known block of one hundred numbers and therefore may be used to provide the thousands and hundreds digits of the line number and, if necessary, the office. Therefore, the three lower armatures of each hundred block relay are used to ground a set of three terminals in a cross-connecting rack 1260. Each set of these terminals is connected to one terminal each in three sets of ten terminals, viz. a set of ten terminals representing the thousands digit, a set of ten terminals representing the hundreds digit and a set of terminals including one terminal for each office, usually two, located in the office building and served by the identifier.

As shown, relay 1200 grounds terminals 1253, 1254 and 1255, thereby connecting ground over terminals 1256, 1257 and 1258 to conductors 1261, 1262 and 1263 which extend through cable 1264 over contacts of relay 1112, to conductors 1161, 1162 and 1163 through cable 1450, contacts of relay 1404, conductors 1483, 1484 and 1485 through the cable 1486 to the office, thousands and hundreds digit registers indicated by the box 1770. The registers 1770 operate to hold these digits after the number group frame has been released. With relay 1704 operated the conductors 1783, 1784 and 1785 outgoing from registers 1770 are extended over contacts of relay 1704 to conductors 1721, 1722 and 1723 through cable 1726 leading over contacts of relays 330 and 301 in the identifier connector to the calling line register 208 where these digits are registered.

Twenty block progress relay 1300 identifies the group of twenty lines including the calling line as the first group including lines having tens digits zero or one while even tens relay 1400 indicates that the line has an even tens digit. Therefore relays 1300 and 1400 cooperate to register the tens digit zero. For this purpose a circuit is closed from ground at the lower contact of relay 1400, conductor 1447, contact 1 of relay 1300, conductor 1370 through cable 1371, contact of relay 1704, conductor 1724 through cable 1726, contacts of identifier connector relays 330 and 301 to the calling line register 208.

The units digit of the calling line number is provided by the units digit register of Fig. 7, relay 701, which was operated and locked, connecting ground over its contact 3 to conductor 728 through cable 721, contact of relay 1704, conductor 1725 and thence through cable 1726 as traced for the other digits to the calling line register 208. When the calling line number has been set up in the register 208, relay 216 operates, releasing the identifier connector and the identifier. The information stored in the sender may now be transferred to the recorder 209.

Tip party

If a subscriber, whose substation, for example substation 101, is the tip party on a line, originates a call the call progresses as previously described. However, since at this substation the ringer is connected directly to ground, the originating sender 123 operates relay 111 in the district junctor 107 and the party identification circuit 207 in sender 205 causes relay 211 to operate.

It may be noted here that the conductors extending the sleeve conductors from the armatures of the twenty block relays are connected to different sets of contacts on the identifier connector relays 1102, 1112, etc. However, since the marker connector relays 1002, 1012, etc. are arranged to extend only one group of twenty sleeve conductors to the marker for test, a relay 1020 is operated, whenever a marker connector relay is operated, to connect together the conductors occupying the corresponding positions in each twenty block so that with one hundred block relay and one twenty block relay operated, just twenty sleeve test circuits will be completed.

Since there are eight twenty block relays, all of which are operated, eight groups of twenty lines are extended to the identifier where each group is divided into two sub-groups of ten each and connected to a tone coil. Consequently, the identifier is equipped with sixteen tone coils. The secondary windings of these tone coils are connected to the sixteen detectors of Fig. 16 by relay 1500. Tone coil 1429 to which the sleeve of the calling line has been extended, is connected to detector 1600, which detects the presence of the identification tone, operating relay 1620. In addition, the operation of relay 1500 connects battery through the lower winding of relay 1600 over conductor 1442, contact of relay 1500, conductor 1542 to the two upper front contacts of relays 1640 to 1647 and connects battery through the lower winding of relay 1601, conductor 1443, contact of relay 1500, conductor 1543 to the two upper contacts of relays 1648 to 1655. Relay 1700 in operating connects ground over the back contact of relay 1406, conductor 1480, contact of relay 1700, conductor 1790 to the uppermost armature of relay 1640 and extends a connection from the open front contact of relay 1406, conductor 1481, contact of relay 1700, conductor 1791 to the second armature of relay 1655. The top armatures of relays 1640 to 1655 are connected in one chain circuit and the second armatures of these relays are arranged in a second chain circuit, so that with relay 1406 normal the even line groups are preferred and with relay 1406 operated the odd line groups are preferred.

When relay 1500 operated it connected ground to the armatures of the polarized relays 1620, etc.

When relay 1620 is operated as above described, a circuit is closed from ground at the contact of relay 1500, to the armature and contact of relay 1620, winding of relay 1640 to battery supplied by the timer 1703 over conductor 1706.

Relay 1640 operates, locks to battery as previously described and closes a circuit from battery over its upper front contact, conductor 1630, contact of relay 1700, conductor 1710 through cable 1711, upper winding of relay 1410, conductor 1444, to ground at the back contact of relay 1406, operating relay 1410. At the same time relay 1640 connects conductor 1542 to conductor 1790, thereby completing the circuit above traced from battery through the winding of relay 1640 to ground at the back contact of relay 1406, operating relay 1406. Relays 1406 and 1410 lock in a circuit which may be traced from ground at the back contact of relay 1406, upper winding and front contact of relay 1406 lower winding and front contact of relay 1410, conductor 1445, contact 1 of relay 608 to the winding of relay 605 and battery, operating relay 605.

Relay 1410 opens the circuit of relay 1405 which releases, opening the circuits of the hundred block relays in the number group circuit and closing an

obvious circuit for relay 1404. Relay 1404 operates, opening the multiple circuit by which the hundred block relays were operated and extending individual circuits from the hundred block relays to the hundred block register relays 1410, etc. For example, the circuit of hundred block relay 1200, now extends from battery through its winding to conductor 1451 as above traced and over a front contact of relay 1404, front contact of relay 1410 to ground on conductor 608, thus reoperating relay 1200 and holding it operated through the subsequent test. Relay 1404 also closes circuits for registering the office, thousands and hundreds digits of the line number as will be pointed out hereinafter.

Relays 1410 and 605 open the operating circuit for relay 600 but that relay remains locked over its contact 2 to off-normal ground. At its front contact relay 605 operates relay 601 which locks under the control of relay 600 and disconnects ground from conductor 607, releasing relays 1730 and 1500. Relay 1500 disconnects the coils 1423, etc. from the detectors 1600, etc. and disconnects ground from the polarized detector relays, thereby releasing relay 1640. Relay 1500 also opens the circuits for relays 1310 and 1311, which control the twenty block progress circuit of Fig. 13. With relay 1310 released, relay 1309 is held operated, and with relay 1311 released the circuit for the twenty block relays is held closed. Relay 1700 disconnects the output relays from the hundred block register relays 1410, etc. but relay 1410 is locked operated as above described.

The identifier is now ready to identify the individual line. With relay 601 operated a circuit is closed from ground at the left front contact of relay 601, conductor 609, back contact of relay 713, back contacts of the units register relays 703, 702, 701, etc. winding of start relay 711 and battery. Relay 711 operates and locks over its contact 7 and back contact of relay 713 to ground on conductor 699 independent of the register relays. Relay 711 closes a circuit from ground over the back contact of relay 712, contacts 8 and 1 of relay 711, conductor 726 through the windings of relay 1701 and 1501 to battery. Relays 1701 and 1501 operate to prepare the input and output circuits of the detectors. Relay 711 at its contacts 2 and 4 opens the circuits for the frame group input relays and prepares circuits for the detector output relays as traced hereinafter.

Hundred block relay 1200 is held operated under the control of relay 1410. With relay 1200 operated alone, only the twenty block relay 1220 is operated under the control of relay 1300. When the even tens relay 1409 operated, it closed an obvious circuit for relay 1402. The sleeves of the lines having the even tens digit are now extended to the detectors. The circuit for the sleeve of the calling line may be traced from the number group cross-connecting rack 900, conductor 940 through cable 942, contact of twenty block relay 1220, conductor 1230 through cable 1240, contact of relay 1112, conductor 1140 through cable 1142, contact of relay 1410, conductor 1446, contact of relay 1402, conductor 1449 through a network comprising condenser 1520 and resistances 1521 and 1522 to ground. Resistance 1522 is connected over contacts of relay 1501 to the input of detector 1600.

Similarly the other nine lines of this group of ten are connected to ground through a pair of resistances and a condenser, with one resistance connected across the input of the corresponding detector. As pointed out in the Carpenter et al.

Therefore, after the identifier has been connected with the sender 205 as above described, ground is connected over the front contact of relay 211, conductor 217, front contacts of relays 301 and 300 in the identifier connector, conductor 346 to the winding of relay 409 and battery, operating relay 409.

With relay 409 operated, relay 408 is operated in a circuit over the front contact of relay 409 and the back contact of relay 412 to ground over conductor 414, and supplies the identification tone as above traced to the conductor 112 and sleeve conductor 119. In the district junctor, however, the tone is extended through condenser 113, front contact of relay 109, back contact of relay 112, front contact of relay 111 to the second metering conductor 121, winding of message register 840 to conductor 850 and coil 910. With relay 409 operated, indicating that a tip party is calling, the identifier prepares to look for tone among the tone coils associated with the metering conductors of the tip parties. Relay 409 closes a circuit from ground on conductor 716, left front contact of relay 409, conductor 422, contact 2 of relay 711, conductor 722, back contact of relay 412, conductor 423, windings of relays 1503 and 1504 to battery. Relays 302 and 303 are operated as above described. With these relays operated, the secondary windings of the tip tone coils 920 etc. of the first group of number group frames are connected over cables 933 and 935, contacts of relay 306, contacts of relay 303, cable 345, contacts of relay 1504 to the first fifteen of the detectors 1600 etc. The metering conductors of both tip and ring parties on message rate lines are connected to the ring tone coils. Therefore, relay 1503 is employed to connect all of the secondary windings of the ring tone coils of the number groups being tested in multiple to detector 1615.

Relays 511, 510 and 1702 are operated as previously described. Had the tip party on a flat rate line such as substation 801 been calling, one of the detectors 1600 to 1614 would have responded to cause the operation of one of the number frame group register relays of Fig. 5 and the identification would have proceeded as above described. Since a message rate line is calling, detector 1615 responds, operating polarized relay 1635 and in turn output relay 1655. Relay 1655 closes a circuit from battery over the upper back contacts of output relays 1649 to 1654, upper front contact of relay 1655, conductor 1661, front contact of relay 1702 conductor 1730 through cable 1708, winding of relay 502, conductor 521 through cable 1708, contact of relay 1702, conductor 1731, lower front contact of relay 1655 to ground. Relay 502 at its contact 7 closes a circuit from ground through the right winding of relay 412 to battery, operating relay 412 which locks through its left winding to off-normal ground.

Relay 412 in operating opens the operating circuit of relays 1503 and 1504, disconnecting the tone coils from the detectors and ground from the armature of relay 1635, thereby restoring detector 1615 and relays 1635, 1655 and 502. At its right front contact, it connects conductor 722, grounded as above described, to conductor 724, thereby operating relay 1502 in the manner previously described and permitting the identification of the number group frame of the calling line as described. The further identification of the calling line and the registration of the line

number take place as described in connection with substation 100.

Number group progress

In the identifications previously described it has been assumed that the calling line was associated with the first group of number group frames. While a number group frame associated with lines having a low call rate may handle as many as eight hundred lines and is so arranged, those associated with lines having heavy incoming traffic are assigned a much smaller number of lines and in consequence there may be several groups of number group frames, each of which may have to be tested to locate the calling line.

For this purpose, a set of progress relays is provided, as shown in Fig. 4. When relay 1702 is operated for the test of the first group of number group frames a circuit is closed from battery through the winding of relay 407, conductor 424, contact of relay 1702 to conductor 1732 leading to the timer 1703. The timer is arranged to connect ground to conductor 1732 a measured time interval following the completion of this circuit, this time interval being sufficient for the detection of the identification tone and the seizure of the number group frame, followed by the release of relay 1702. If relay 1702 remains operated long enough for the timer to ground conductor 1732, relay 407 is operated in the above traced circuit.

When relay 407 operates, it completes a circuit from ground at the right front contact of relay 408, front contact of relay 407, contact 3 of relay 403, contacts 1 of relay 401 and 402 to battery through the winding of relay 405. Relay 405 operates, locks over its No. 6 contact and opens the operating circuits for the first group relays 302, 303 and 410. Relay 410 releases, opening the circuit of relay 1702, which opens the circuit of relay 407. When relay 407 releases, a circuit is closed from ground at the front contact of relay 408, back contact of relay 407, contact 7 of relay 400, contact 7 of relay 404, contact 5 of relay 405 to the winding of relay 402 and battery. Relay 402 operates, locking over its contact 5 and contact 7 of relay 405 and closing circuits from ground on conductor 517 over contacts 2 and 4 of relay 405, contacts 3 and 4 of relay 402 and contacts 1 and 3 of relay 404 to operate relays like relays 302, 303 and 410 associated with the second group of number group frames. As before, the relay like relay 410 operates relay 1702, reestablishing the circuit between the timer and relay 407 to measure a time interval sufficient for the test for the identification tone on these frames. If a sufficient time elapses, relay 407 reoperates, operating relay 404 to release the second group relays, releasing relay 407

and operating relay 401. Relays 404 and 401 lock and extend ground on conductor 517 to the windings of relays 304, 305 and 411. Relay 411 also operates relay 1702 to establish the timing circuit for relay 407. If relay 407 again operates, it operates relays 400 and 403, extending the ground on conductor 517 over contacts 2 and 4 of relay 405, contacts 3 and 4 of relay 402, contacts 2 and 4 of relay 404, contacts 3 and 4 of relay 401, contacts 2 and 4 of relay 400 and thence over contact 1 of relay 403 to the winding of relay 405 and battery. Relay 406 serves to record the fact that no tone was found and to cause the timer to function to bring about a second trial.

If there are a sufficient number of frames to require it, an additional pair of relays like relays

402 and 404 may be inserted at the dotted lines.

Means is provided in the case of each step of the identification to make a second trial if the first trial is not successful within a predetermined interval. For example, if the identifier fails to find the number group frame to which the identification tone has been applied, relay 406 operates as above described, signalling the timer. The timer then applies a momentary ground to conductor 1733 over a contact of relay 1702, conductor 1734 to the winding of relay 513 and battery. Relay 513 operates in this circuit, locking over conductor 522 to ground at a contact of relay 1702. Relay 513 opens the operating and locking circuits for relay 511 causing that relay to release and disconnect ground from conductor 517, releasing the group progress relays, the group cut-in relays and relay 1702. Relay 513 closes a circuit from battery through the winding of relay 515, back contact of relay 514, contact 3 of relay 513 to off-normal ground. Relay 515 operates in this circuit locking through the winding of relay 514 to off-normal ground, independent of relay 513. However, relay 514 cannot operate being shunted by the operating ground for relay 515. When the group relays have released, in turn releasing relay 1702, the locking circuit of relay 513 is opened and that relay releases opening the shunt around the winding of relay 514. Relay 514 now operates, again closing the operating circuit for relay 511 and permitting another attempt to be made to find the number group frame.

A similar arrangement is provided in Fig. 6 for permitting second attempts to locate the group of twenty lines.

Twenty block progress

In describing the identification of line 100, it was assumed, for convenience, that the last two digits were zero-zero so that the identification tone was detected while the first twenty block progress relay was operated.

With relay 1500 operated a circuit is closed from battery through the winding of relay 1311, conductor 1512, front contact of relay 1500, conductor 1511 to the timer 1703. A predetermined time after the closure of this circuit, sufficient for detection of the identification tone and the operation of the hundred block register relay, the timer 1703 connects ground to conductor 1511, operating relay 1311. With relay 1311 operated, a locking circuit is closed for relay 1300 over contact 7 of relay 1300, contact 5 of relay 1312 to ground over contact 2 of relay 1311. At contact 4, relay 1311 opens the normally closed circuit of relay 1310 and that relay releases to provide a supplementary locking ground for relay 1300. At contact 1, relay 1311 extends ground over contact 1 of relay 1312, contact 10 of relay 1300 to the lower winding of relay 1301 and battery. Relay 1301 operates in this circuit, locking over its contact 8, contact 9 of relays 1302, 1303 and 1304, contact 3 of relay 1312, conductor 1510, contact of relay 1500, conductor 1441, back contacts of the hundred block register relays to ground on conductor 608.

In the meantime, relay 1311 at contact 3 disconnected ground from conductor 1313 releasing the first twenty block relay in each hundred block. After a short interval ground is removed from conductor 1512 releasing relay 1311. With relay 1311 released relay 1310 is reoperated and the locking circuits of relay 1300 are opened and that relay releases. When relay 1311 closes its back

contacts it connects ground at its contact 3 over contact 3 of relay 1301 to conductor 1314 to operate the second twenty block relay in each hundred block. If the identifier is not advanced by the detection of tone in these groups of lines relay 1311 is reoperated, holding relay 1301 operated, operating relay 1302 and releasing the second twenty block relays. The operation of relay 1302 opens the original holding circuit for relay 1301 so that, when relay 1311 releases, relay 1301 also releases and the third set of twenty block relays is operated. Similarly, relays 1303 and 1304 are operated in turn to cause the operation of the fourth and fifth sets of twenty block relays to connect the corresponding sleeve leads for test. If, for example, the calling line has nine for its tens digit, the tone on its sleeve conductor will be to one of the detectors 1609 to 1615 when relay 1304 and the fifth set of twenty block relays 1214, 1224, etc. is operated, resulting in the operation of one of the output relays 1649 to 1655 and odd relay 1401. Relay 1401 operated connects ground over conductor 1448, contact 2 of relay 1304 to conductor 1379 to transmit the tens digit nine to the calling line register.

As above described, relay 1310 is operated over contact 4 of relay 1311 and conductor 1510 while relay 1311 is normal. When relay 1311 operates, relay 1310 releases to supplement the ground furnished by relay 1311 to hold the previously operated progress relay. When one of the hundred block register relays operates, ground is disconnected from conductor 1510 so that relay 1310 is released holding the progress relay operated independent of relay 1311 until the tens digit has been transmitted and the identifier released. When relay 1701 operates at the start of units identification, it closes a circuit for relay 713 similar to that traced for relay 513. If the identifier fails to find the line in the group being tested, as a result of locating the wrong party where both parties appear in the same number group or of locating the second party on a line being identified by a different identifier, relay 713 will be operated by the timer 1703. Relay 713 locks under the control of relay 1701 and prepares the identifier to hunt for another block of twenty lines having tone thereon. In order to prevent identifying the wrong twenty block again, the circuit is arranged to reverse the order of test and the order of preference. Relay 713 closes a circuit from battery through the winding of relay 715 contact 2 of relay 714, contact 3 of relay 713 to off-normal ground. Relay 715 operates in this circuit and locks through the winding of relay 714, contact 1 of relay 715 to off-normal ground, but relay 714 is prevented from operating by the operating circuit of relay 715. Relay 713 opens the locking circuit of relay 711, while relay 715 opens the locking circuit of relay 600 thereby placing the identifier in condition to make another search for the group of twenty lines including the calling line. The release of relay 711 opens the circuit of relay 1701, thereby in turn releasing relay 713 and permitting relay 714 to operate. Relay 714 at contact 1 prepares an alternative locking circuit for relay 600 and, at contact 3 connects ground to conductor 727, operating relays 1312 and 1406. Relay 1406 disconnects ground from conductor 1480 and connects it to conductor 1481 thereby reversing the preference between the even and odd tens relays. It also disconnects ground from one side of the windings of the hundred block register relays and connects battery to the other

side of their windings, reversing the order of preference of the hundred block relays.

Relay 1312 operated, causes the twenty block steering relays to be operated in the reverse order. Ground on conductor 1510 is extended over contact 4 of relay 1312, over contacts 6 of relays 1300, 1301, 1302 and 1303 to the upper winding of relay 1304 and battery. Therefore ground over contact 3 of relay 1311 is extended first over contact 3 of relay 1304 to conductor 1316 through cable 1315, contact of relay 1112, conductor 1154 and over the front contacts of hundred block relays 1200 to 1207 to the windings of the fifth twenty block relays 1214, 1224, etc.

If relay 1311 is operated because the calling line is not included in any of these lines tested; ground is extended over contact 1 of relay 1311, contact 2 of relay 1312, contact 5 of relay 1304 to the upper winding of relay 1303 and battery, thereby preparing to operate the fourth set of twenty block relays to test the corresponding groups of lines. In a similar manner, relays 1302, 1301 and 1300 may be operated in turn under the control of relay 1311.

Interference between identifiers operating simultaneously would be cared for in substantially the same manner as in the above identified Gooderham application.

What is claimed is:

1. In a telephone system, subscribers' lines having numerical designations, automatic switches, control equipment for operating said automatic switches to establish connections with said lines, means in said control equipment for recording the designation of one of said lines when called, number group circuits associated with said lines, means in said control equipment operated in accordance with said recorded designation for seizing one of said number group circuits and operating said seized circuit to establish a test circuit for said called line, a toll trunk, means responsive to a call from one of said lines for connecting said calling line to said toll trunk over said automatic switches, registering means associated with said trunk, identifying means operated under the control of said registering means to seize the number group circuit associated with said calling line, and means in said one identifying means to operate the seized number group circuit to establish a circuit for identifying said calling line.

2. In a telephone system, subscribers' lines having numerical designations, automatic switches, control equipment, for operating said automatic switches to establish connections with said lines, means in said control equipment for recording the designation of one of said lines when called, number group circuits associated with said lines, a sleeve terminal and a message register terminal for each line in said number group circuit, means in said control equipment operated in accordance with said recorded designation for seizing one of said number group circuits and operating said seized circuit to establish a test circuit for said called line over said sleeve terminal, a toll trunk, means responsive to a call from one of said lines for connecting said calling line to said toll trunk over said automatic switches, registering means associated with said trunk, identifying means operated under the control of said registering means to identify the number group circuit associated with said calling line over said message register terminal and to seize said number group circuit and means in said identifying means to operate the seized

number group circuit to connect with said sleeve terminals for identifying said calling line.

3. In a telephone system, subscribers' lines, a plurality of substations on said lines, each having numerical designations, automatic switches, control equipment for operating said automatic switches to establish connections with said lines, means in said control equipment for recording the designation of one of said lines when called, number group circuits associated with said lines, a sleeve terminal and a message register terminal for each substation in said number group circuit, means in said control equipment operated in accordance with said recorded designation for seizing one of said number group circuits and operating said seized circuit to establish a test circuit for said called line over one of said sleeve terminals, a toll trunk, means responsive to a call from one of said lines for connecting said calling line to said toll trunk over said automatic switches, registering means associated with said trunk including means for determining which substation is calling, identifying means, means to associate said identifying means with said registering means, means in said identifying means to mark the sleeve terminals and message register terminals of said substations on said calling line, means under the control of said determining means to cause said identifying means to identify the number group circuit associated with said calling substation over said message register terminal and to seize said number group circuit, and means in said identifying means to operate the seized number group circuit to connect with said sleeve terminals for identifying said calling substation.

4. In a telephone system, subscribers' lines having numerical designations, a sleeve terminal and a message register terminal individual to each line, said lines arranged in groups, a toll trunk, means for connecting a calling one of said lines with said toll trunk, registering means associated with said trunk, identifier means, means in said identifier operated over said message register terminal to identify the line group of said calling line, means operated over said sleeve terminal to identify said calling line and means under the control of said group identifying means and said line identifying means to transmit the designation of said calling line to said registering means.

5. In a telephone system, subscribers' lines having numerical designations, a sleeve terminal and a message register terminal individual to each line, said lines arranged in groups, a toll trunk, means for connecting a calling one of said lines with said toll trunk, registering means associated with said trunk, identifier means, means to associate said identifier means with said trunk, means in said identifier to mark the sleeve terminal and the message register terminal of said calling line over said trunk, means in said identifier operated over said message register terminal to identify the line group of said calling line, means operated over said sleeve terminal to identify said calling line and means under the control of said group identifying means and said line identifying means to transmit the designation of said calling line to said registering means.

6. In a telephone system, subscribers' lines having numerical designations, a sleeve terminal and a message register terminal individual to said line, a plurality of cross-connecting frames, each frame having a terminal individual to each of a

plurality of groups of consecutive numbers and a message register terminal individual to the frame, means for connecting the sleeve terminal of a line with the corresponding number terminal, and the line message register terminal with the message register terminal of the same frame, a toll trunk, means for connecting a calling one of said lines with said toll trunk, registering means associated with said trunk, identifier means, means to associate said identifier means with said trunk, means in said identifier to mark the sleeve terminal and the message register terminal of said calling line over said trunk, and thereby a number terminal and the message register terminal of a particular frame, means in said identifier operated over said frame message register terminal to identify the frame to which the sleeve of said calling line is attached, means to connect said identifier with said frame, means operated over said number terminal to identify said calling line and means under the control of said frame connecting means and said line identifying means to transmit the designation of said calling line to said registering means.

7. In a telephone system, subscribers' lines having numerical designations, a sleeve terminal and a message register terminal individual to each line, said lines arranged by frames, groups and subgroups, a toll trunk, means for connecting a calling one of said lines with said toll trunk, registering means associated with said trunk, identifier means, means in said identifier, operated over said message register terminal to identify the frame of said calling line, means to connect said identifier with said frame, a plurality of sets of networks and a set of detectors in said identifier, means to successively connect said sets of networks with the sleeve terminals of said group of lines and said subgroups of lines and at the same time with said detectors, means under the control of said detectors to identify said calling line and means under the control of said frame identifying means and said line identifying means to transmit the designation of said calling line to said registering means.

8. In a telephone system, subscribers' lines having numerical designations, a sleeve terminal and a message register terminal individual to each line, a plurality of cross-connecting frames, each frame having a terminal individual to each of a plurality of groups of consecutive numbers and a message register terminal individual to the frame, means for connecting the sleeve terminal of a line with the corresponding number terminal, and the line message register terminal with the message register terminal of the same frame, a toll trunk, means for connecting a calling one of said lines with said toll trunk, registering means associated with said trunk, identifier means, means to associate said identifier means with said trunk, means in said identifier to mark the sleeve terminal and the message register terminal of said calling line over said trunk, and thereby a number terminal and the message register terminal of a particular frame, means in said identifier operated over said frame message register terminal to identify the frame to which the sleeve of said calling line is attached, means to connect said identifier with said frame, a plurality of sets of networks and a set of detectors in said identifier, means to successively connect said sets of networks with the number terminals of said groups of lines by groups and individually and at the same time with said detectors, means under the control of said detectors to identify

said calling line and means under the control of said frame identifying means and said line identifying means to transmit the designation of said calling line to said registering means.

9. In a telephone system, subscribers' lines having numerical designations and location designations, automatic switches, control equipment for operating said automatic switches to establish connections with said lines, means in said control equipment for recording the numerical designation of one of said lines when called, number group circuits associated with said lines, means in said control equipment operated in accordance with said recorded numerical designation for seizing one of said number group circuits and operating said seized circuit to translate said numerical designation into said location designation, a toll trunk, means responsive to a call from one of said lines for connecting said calling line to said toll trunk over said automatic switches, registering means associated with said trunk, identifying means operated under the control of said registering means to seize the number group circuit associated with said calling line, and means in said one identifying means to operate the seized number group circuit to establish the numerical designation of said calling line.

10. In a telephone system, subscribers' lines having tip and ring substations thereon, each substation having a numerical designation, a sleeve terminal individual to each line, certain of said lines having a message register terminal individual to each substation, others of said lines having a single message register terminal, a plurality of cross-connecting frames, each frame having a terminal individual to each one of a plurality of groups of consecutive numbers and a first and second message register terminal individual to the frame, each of said certain lines having its sleeve terminal connected to the number terminals corresponding to the designations of the substations on said line and the message register terminals connected to the first of the associated frame message register terminals, each of said other lines having its sleeve terminal connected to the number terminals corresponding to the designations of the substations on said line and the single message register terminal connected in multiple to the first message register terminal of the frame on which said ring substation number appears and to the second message register terminal on the frame on which said tip substation number appears, a trunk circuit, means for connecting a calling one of said lines with said trunk, an identifier, means to associate said identifier with said trunk, means operated over said trunk to indicate to said identifier whether the tip or ring substation is calling, means in said identifier to mark the sleeve terminal of said calling line and the message register terminal of the calling substation over said trunk and thereby the corresponding number terminals and message register terminal or terminals on said frames, a plurality of detectors in said identifier, means in said identifier responsive to an indication that a tip substation is calling to connect one of said detectors to said first frame message register terminals in multiple and the remaining detectors to said second frame message register terminals individually, and means responsive to the operation of one of said remaining detectors to connect said identifier with the corresponding frame to complete the identifica-

tion of the calling substation over the marked number terminal.

11. In a telephone system, subscribers' lines having tip and ring substations thereon, each substation having a numerical designation, a sleeve terminal individual to each line, certain of said lines having a message register terminal individual to each substation, others of said lines having a single message register terminal; a plurality of cross-connecting frames, each frame having a terminal individual to each one of a plurality of groups of consecutive numbers and a first and second message register terminal individual to the frame, each of said certain lines having its sleeve terminal connected to the number terminals corresponding to the designations of the substations on said line and the message register terminals connected in multiple to the first of the associated frame message register terminals, each of said other lines having its sleeve terminal connected to the number terminals corresponding to the designations of the substations on said line and the single message register terminal connected in multiple to the first message register terminal of the frame on which said ring substation number appears and to the second message register terminal on the frame on which said tip substation number appears, a trunk circuit, means for connecting a calling one of said lines with said trunk, an identifier, means to associate said identifier with said trunk, means operated over said trunk to indicate to said identifier whether the tip or ring substation is calling, means in said identifier to mark the sleeve terminal of said calling line and the message register terminal of the calling substation over said trunk and thereby the corresponding number terminals and message register terminals on said frames, a plurality of detectors in said identifier responsive to an indication that a tip substation is calling to connect one of said detectors to said first frame message register terminals in multiple and the remaining detectors to said second frame message register terminals individually, means responsive to the operation of one of said remaining detectors to connect said identifier with the corresponding frame to complete the identification of the calling substation over the marked number terminal, means responsive to the operation of said one detector to disconnect said detectors from said second frame message register terminals and to connect said detectors with said first frame message register terminals individually and means responsive to the operation of one of said detectors over one of said first frame message register terminals to connect said identifier with the corresponding frame to complete the identification of the calling substation over the marked number terminal.

12. In a telephone system, subscribers' lines, a plurality of substations on said lines, each having numerical designations, automatic switches, number group circuits associated with said lines, a sleeve terminal and a message register terminal for each substation in said number group circuit, a toll trunk, means responsive to a call from one of said lines for connecting said line to said toll trunk over said automatic switches, registering means associated with said trunk including means for determining which substation is calling, an identifier, means to associate said identifier with said registering means, means in said identifier to mark the sleeve terminals and message register terminals of both substations on said calling line, means to cause said identifying means to identify the number group circuit associated with said substation over said message

the number group circuit associated with said substation over said message register terminal and to seize said number group circuit, a plurality of detectors in said identifier, means to successively connect a plurality of groups of said sleeve terminals with said detectors, means controlled by the operation of one of said detectors in detecting a group containing a marked sleeve terminal to connect the sleeve terminals of the group individually to said detectors, a class terminal associated with each sleeve terminal in said number group circuit, and means operated over said determining means and said class terminal in response to the operation of one of said detectors in detecting an individual marked sleeve terminal to record the identity of said individual sleeve terminal.

13. In a telephone system, subscribers' lines, a plurality of substations on said lines, each having numerical designations, automatic switches, number group circuits associated with said lines, a sleeve terminal and a message register terminal for each substation in said number group circuit, a toll trunk, means responsive to a call from one of said lines for connecting said line to said toll trunk over said automatic switches, registering means associated with said trunk including means for determining which substation is calling, an identifier, means to associate said identifier with said registering means, means in said identifier to mark the sleeve terminals and message register terminals of both substations on said calling line, means to cause said identifying means to identify the number group circuit associated with said substation over said message register terminal and to seize said number group circuit, a plurality of detectors in said identifier, means to successively connect a plurality of groups of said sleeve terminals with said detectors, means controlled by the operation of one of said detectors in detecting a group containing a marked sleeve terminal to connect the sleeve terminals of the group individually to said detectors, a class terminal associated with each sleeve terminal in said number group circuit, means operated over said determining means and said class terminal in response to the operation of one of said detectors in detecting an individual marked sleeve terminal to record the identity of said individual sleeve terminal, and means effective if said recording means is not operated in response to the operation of said detector in detecting an individual marked sleeve terminal to repeat the connection of said detectors to said groups of sleeve terminals and to said individual sleeve terminals to identify the sleeve terminal for the other substation on said calling line.

14. In a telephone system, subscribers' lines, a plurality of substations on said lines, each having numerical designations, automatic switches, number group circuits associated with said lines, a sleeve terminal and a message register terminal for each substation in said number group circuit, a toll trunk, means responsive to a call from one of said lines for connecting said line to said toll trunk over said automatic switches, registering means associated with said trunk including means for determining which substation is calling, an identifier, means to associate said identifier with said registering means, means in said identifier to mark the sleeve terminals and message register terminals of both substations on said calling line, means to cause said identifying means to identify the number group circuit associated with said substation over said message

23

register terminal and to seize said number group circuit, a plurality of detectors in said identifier, means to successively connect a plurality of groups of said sleeve terminals with said detectors in one order, means controlled by the operation of one of said detectors in detecting a group containing a marked sleeve terminal to connect the sleeve terminals of the group individually to said detectors, a class terminal associated with each sleeve terminal in said number group circuit, means operated over said determining means and said class terminal in response to the operation of one of said detectors in detecting an individual marked sleeve terminal to record the identity of said individual sleeve terminal, and means effective if said recording means is not operated in response to the operation of said detector in detecting an individual

24

marked sleeve terminal to repeat the connection of said detectors to said groups of sleeve terminals in the reverse order and to said individual sleeve terminals to identify the sleeve terminal for the other substation on said calling line.
